TOY LOCOMOTIVE

Robert Genin, Scarsdale, N.Y., assignor to Child Guidance Toys, Inc., New York, N.Y., a corporation of New York

Filed Apr. 5, 1967, Ser. No. 6,531

Term of patent 14 years

(Cl. D34—15)

FIG. 3

FIG. 4

FIG. 1 is a perspective view of my design for a toy locomotive having a transparent body which exposes the operating gears therein;

FIG. 2 is a front view of the toy locomotive;

FIG. 3 is a plan view of the locomotive;

FIG. 4 is a side view of the locomotive, the internal gears being visible through the transparent body; and

FIG. 5 is a rear view of the toy locomotive.

I claim:

The ornamental design for a toy locomotive, substantially as shown and described.
